TAG FASTENER

Filed Feb. 28, 1936

FIG. 1.

FIG. 2.

FIG. 3.

FIG. 4.

INVENTOR:
Samuel Weiss,

BY
Israel Benjaminis,
ATTORNEY

UNITED STATES PATENT OFFICE

2,061,927

TAG FASTENER

Samuel Weiss, Brooklyn, N. Y.

Application February 28, 1936, Serial No. 66,245

6 Claims. (Cl. 40—24)

My invention relates to improvements in tag fasteners and it consists in the novel features which are hereinafter described.

One of the objects of my invention is to provide a fabric tag with perfected means for fastening the same to a garment or a piece of linen in a way to prevent the accidental disengagement of the garment from the fastener.

Another object is to reduce the length of time and the effort required for connecting a tag to a garment.

A further object of my invention is to reduce the extent of the opening in a garment which is produced therein by connecting the fastener thereto.

A still other object is to prevent the laceration of garments and of the hands of operators by the protrusion of sharp points from the fastener.

Another object of my invention is to have said tag fastener simple, durable and inexpensive.

Other objects and advantages will hereinafter appear.

I attain these objects by the tag fastener, three forms of which are illustrated in the accompanying drawing or by any mechanical equivalent or obvious modification of the same.

In the drawing Fig. 1 is a front elevation partly in section, of one form of my improved tag fastener; Fig. 2 is a side elevation or edge view of the same, looking from left to right in Fig. 1; and Fig. 3 is a detail view in cross-section on the line 3—3 of Fig. 1, looking in the direction of the arrows and drawn to a larger scale than Figs. 1 and 2.

Fig. 4 is a front elevation partly in section of another form of my tag fastener.

Fig. 5 is a detail view in cross-section on the line 5—5 of Fig. 4, looking in the direction of the arrows and drawn to a larger scale than Fig. 4.

Similar numerals refer to similar parts throughout the several views:

11—12 are the two prongs or legs and 13a the base of a tag fastener of the form which is shown in Figs. 1, 2, and 3.

The prongs 11 and 12 are made of spring wire and are initially stressed; they have thereon inclined portions 13 and 14 respectively, which cross each other, and outer portions 15 and 16 which may be substantially parallel to each other.

The portion 15 terminates in an engaging member 17 which is shown as substantially at right angles to the member 15 and in engagement with a fabric or garment 10, a small part 55 of which is shown.

The portion 16 terminates in a bent end 18 which is enclosed by a socket 21 at the rear end of a relatively long housing 19, which terminates at the forward end thereof in a flare 20.

The housing 19—20—21 may be made of sheet metal and connected to the said end 18 as shown in Fig. 1.

The pointed end of the engaging member 17 is disposed to engage a fabric or garment and extends into the housing 19—20 sufficiently far to insure the retention of the said pointed end in said housing under all working conditions and the end of the member 17 may be withdrawn from the housing 19 only by the application of manual effort in a suitable direction. The working stresses due to centrifugal force acting on garments are disposed at right angles to the said member 17, and will not affect the retention of the end of said member 17 in said housing 19. The garment is, therefore, securely held by the above described fastener which ordinarily has a suitable tag connected to the base 13a thereof.

In the form of my tag fastener, which is shown in Figs. 4 and 5, 41 and 42 are the prongs and 43 is the base of the fastener; the prongs 41 and 42 are made of spring wire, are initially stressed and have thereon inclined portions 44 and 45 respectively and outer portions 46 and 47.

The portion 46 terminates in an engagement member 48, which is shown in Fig. 4 as connected to a fabric or garment 60, a small part of which is shown in the drawing.

The portion 47 terminates in a bent end 49 which is enclosed by a socket 52 at the rear of a relatively long hood 50 which encloses the pointed end of the member 48 and has thereon at the front thereof a perforated outwardly concave face plate 51 which serves to guide the end of the member 48 through the orifice or opening 53 into the said hood 50, which is open at the lower end thereof.

The plate 51 assists the end of the member 48 to puncture a fabric or garment placed therebetween.

The operation of the tag fastener shown in Fig. 4 is otherwise similar to that of Fig. 1.

The bases 13a and 43 may have thereon each one or more helical coils, if desired.

Other variations are possible and parts of my invention may be used without other parts.

I do not, therefore, restrict myself to the details as shown in the drawing.

I claim as my invention and desire to secure by Letters Patent:

1. In a tag fastener a pair of prongs made of

- wire, outer portions thereon, one of said portions terminating in an engaging member to be connected to a fabric or garment, the other portion having secured thereto a relatively long sheet
- 5 5 metal housing, for enclosing therein the outer end of said member, and said end extending into the said housing sufficiently far to insure the retention of said end in said housing under all working conditions, thereby preventing the accidental removal therefrom of the said fabric or garment.
- 10 2. In a tag fastener a pair of prongs, outer portions thereon, one of said portions terminating in an engaging member to be connected to a fabric or garment, the other portion having thereon a relatively long housing for enclosing therein the outer end of said member, said housing having thereon a part which is clamped upon the end of said other portion, and said outer end
- 15 20 extending into said housing sufficiently far to insure the retention of said outer end in said housing under all working conditions, thereby preventing the accidental removal therefrom of the said fabric or garment.
- 25 3. The elements of claim 2, said housing having a substantially tubular shape in cross section.
4. The elements of claim 2, said housing having a flare at the forward end thereof for guiding the end of said member thereinto.
- 30 5. In a tag fastener a pair of prongs, outer portions thereon, one of said portions terminating in an engaging member to be connected to a fabric or garment, the other portion having thereon a relatively long housing for enclosing therein the outer end of said member, said housing having the shape of a hood which is closed at the top and sides thereof and open at the lower side thereof, and said end extending into the said housing sufficiently far to insure the retention of said end in said housing under all working conditions, thereby preventing the accidental removal therefrom of said fabric or garment.
- 6 10 15 20 25
6. In a tag fastener a pair of prongs, outer portions thereon, one of said portions terminating in an engaging member to be connected to a fabric or garment, the other portion having thereon a relatively long housing for enclosing therein the outer end of said member, said housing having at the forward end thereof a centrally perforated outwardly concave face plate to guide the end of said member through the said perforation into the said housing, and said end extending into the said housing sufficiently far to insure the retention of said end in said housing under all working conditions, thereby preventing the accidental removal therefrom of the said fabric or garment.
- 15 20 25

SAMUEL WEISS.
